COLOR TELEVISION PICTURE TUBE

Jan A. Rajchman, Princeton, N. J., assignor to
Radio Corporation of America, a corporation
of Delaware

Application March 23, 1950, Serial No. 151,397

17 Claims. (Cl. 313—68)

1

This invention relates to television picture tubes. More particularly, it relates to an improved picture tube capable of producing full color images.

The usual color-kinescope comprises an electron-gun and an electron-sensitive color screen or "target" upon which the gun is trained. The color screen may comprise a transparent foundation surface containing many duplicate groups of two or more sub-elementary areas. The respective areas of each group are constituted of different phosphor materials, each of which emits light of a particular color (e. g., red, green or blue) when struck by the electrons from the gun. In a kinescope of this kind it is difficult to make sure that the beam shall at all times impinge upon the particular sub-elementary area upon which it should impinge.

A first object of the present invention is to provide a color television picture tube the successful operation of which does not require unusual precision in the scanning of its electron beam.

A further object is to provide a tube of the kind mentioned above whose operation is not easily disturbed by stray fields.

Still another object is to provide a tube of the kind mentioned above which is operable with less than the customary amount of deflection power.

In general, the above objects are attained as follows: As indicated above, the fluorescent screen is made up of a great many very small sub-elementary coatings. The individual coatings may be dot-like "patches" of pin-point size or strips of hair-line thinness. They are positioned in an image surface to form groups having combined areas corresponding to black-and-white "picture elements." The groups in turn are positioned in a pattern of parallel lines corresponding to the image raster. The tube is so arranged that to reach any part of the image surface the electron beam must (in fact or in effect) first pass through an apertured plate. In passing through the plate the beam is split into a number of adjacent parallel jets. The apertures are small enough and close enough together so that a beam focused as sharply as in black-and-white practice (for an image of equal size) will be split into at least as many jets as the number of sub-elementary coatings in each of the groups. There is a different aperture for each sub-elementary coating in each "picture element." Moreover, the apertures are so positioned in the plate and the plate is so positioned

2

with respect to the image surface that each jet will necessarily bombard a particular coating and not any other. The different colors in which the coatings in each group fluoresce appear to be mixed when viewed from a distance. Moreover, this is true whether these coatings are energized simultaneously or in sequence at a high cyclical rate. A means is provided whereby each of a plurality of separate color signals is effective to control selectively only jets which bombard the same kind of coatings. Thus, each color signal controls all light emissions of a particular color. The means for selectively controlling the electron jets comprises a laminated control assembly of closely-spaced multi-apertured electrodes, including the above-mentioned apertured plate. Some of the electrodes are herein referred to as selective "retarding" electrodes. The term selective is used since each of these electrodes effectively retards only selected jets which cause emission of one particular color. And the word "retarding" is used in this manner because these electrodes do not actually retard but only effectively do so. More specifically, each of these electrodes absorbs high-speed jets in certain selected locations on one of its sides and emits low-speed jets of secondary electrons from corresponding locations on its other side. A control electrode is positioned in front of each of these retarding electrodes to cover its entire front surface. During operation, this electrode is so biased that a video signal which is applied to it is able to influence, i. e., current-modulate, low speed jets which pass through its apertures. Each and every jet into which the beam is subdivided during every fully-scanned raster gets to be "retarded" at one or another of the retarding electrodes and thereby becomes controllable by the associated control electrode thereof.

40 In the drawing:

Fig. 1 represents an embodiment of the invention partly taken in section;

Fig. 2 is an enlarged sectional view of a portion of the control assembly of Fig. 1;

Fig. 3 represents another embodiment of the invention, also partly taken in section;

Fig. 4 is an enlarged sectional view of a portion of the control assembly of Fig. 3;

Fig. 5 is a front view of a control assembly;

50 Figs. 6, 7, and 8 represent different patterns in which sub-elementary coatings may be arranged to form screens suitable for use in the present invention; and

Fig. 9 is an enlarged sectional view of a portion 55 of a fluorescent target.

The picture tube 10 shown in Fig. 1 includes an envelope 11 having a neck 12, a frustum 13 and a window 14. Within neck 12 there is mounted an electron gun 15. It is directed toward the back of a control assembly 16 which is supported behind window 14 by any suitable means (not shown). A target 17 is mounted on the side of assembly 16 farthest from electron gun 15. Target 17 comprises a glass support plate 18, a transparent conductive coating 19 on the back thereof, such as a nesa coating, and a great many dot-like or line-like sub-elementary fluorescent coatings R, B, G. In the description which follows (but not in the claims), "coating" will mean coatings of the dot type unless they are specifically otherwise designated. Each of the coatings R, B and G emits light of a different hue in response to electron bombardment. However, if desired, a single uniform fluorescent coating 50 may be used as shown in Fig. 9. Such a single coating can be used in combination with a multi-sub-element optical filter, for example a filter made of elementary parts R', B', G' each of which selectively transmits light of a predetermined color. A conductive coating 20 carried on the inside of conical portion 13 serves as an accelerating electrode.

In the operation of tube 10 a beam of electrons from gun 15 is caused to trace a raster pattern over the back of assembly 16. Assembly 16 has as many individual back-to-front passageways for electron jets as the total number of sub-elementary coatings R, G and B. Target 17 is mounted on the front of assembly 16 in such a position that each of its coatings R, G, and B is in exact alignment with a different passageway. These passageways and the spacings between them are so small that at any instant of time, the beam will strike the backs of several of them to be subdivided into an equal number of jets. Each passageway is defined by a row of exactly aligned apertures formed in the respective electrodes occurring from the back to the front of assembly 16.

The electrode nearest to gun 15 in assembly 16 is a normalizing electrode 21. Its use overcomes difficulties caused by the fact that the scanning beam from gun 15 does not impinge upon all parts of the back of structure 16 at right angles thereto. Without this electrode, electrons might enter some of the passageways at angles so far from normal as not to be able to go all the way through. Practical tests were made in which the back surface of a normalizing electrode 21 was bombarded with fast primary electrons at a variety of angles of incidence. Under these conditions, secondary electrons emerged from the opposite side at such low velocities that with a little forward acceleration they followed normal paths.

Normalizing electrode 21 includes a thin aluminum film (or foil) 23 which is carried on one side of a multi-apertured plate 22 and covers all of its apertures. This film may be formed by first wetting the back of plate 22 with a thin solution of organic material, e. g., lacquer, so that its apertures are bridged by minute amounts thereof which are stretched into thin films by surface tension. After the solution has dried, the aluminum film 23 is evaporated on top of it. Later, for example in de-gassing of the completed tube, the lacquer will be baked out.

Immediately in front of normalizing electrode 21 in the order named are a back selective retarding electrode 24 and a back control electrode

25. Each comprises an apertured plate having a pattern of apertures exactly like that of plate 22. However, a selected one-third of the apertures of the back retarding electrode 24 are covered by individual secondary-emitter films 26. Each of the covered apertures of electrode 25 is aligned with a different one of the R sub-elementary coatings. (Or, where the coatings are of the strip type, individual rows of the covered apertures are aligned with different R strips.) Thus, where the target 17 is either of the type shown in Fig. 6 or in Fig. 7, the apertures for all of the electrodes should be positioned in parallel horizontal rows and all of the apertures of every third horizontal row should be covered with secondary emitter films 26.

The desired pattern of secondary emitter films 26 may be obtained by the use of the masks suitable for forming (in a manner to be described below) the G and B sets of sub-elementary coatings. For example, the retarding electrode 24 is first made to be just like the normalizing electrode 21. Thereafter, a mask suitable for settling the G set of coatings is placed over the electrode to expose the positions of one-third of the covered apertures. Then a compressed air jet is played over the mask to blow out the parts of the aluminum film in these exposed positions. And finally, the last two steps may be repeated with a mask suitable for settling the B set of coatings.

The pattern of films may also be obtained by using a single mask for causing the evaporated film of aluminum to be deposited only where wanted. The apertures of this kind of mask are positioned in the pattern desired for the films and they are larger than the apertures in the electrodes of assembly 16. Of course, all the apertures of electrode 24 will temporarily be covered with lacquer. However, the ones not covered by films 26 will be opened by heat, e. g., during de-gassing.

The control electrode 25 comprises simply a smooth plate having the same pattern of apertures as plate 22, i. e., as all of the other electrodes in assembly 16. These plates can be made with accuracy and uniformity in a number of known ways. For example, they may be made by a photo-etching process. According to this process an exact replica of the screen is first drawn with pen and ink, this being done on a scale very much larger than one-to-one, if it will be helpful (for attaining precision); a reduced facsimile of the replica is photographically produced if necessary; the thin copper sheet is coated with a photo-sensitive material such as a photo-sensitive material which contains albumen, whereby it is adapted to harden on exposure to light; a light-image of the replica is projected onto the copper sheet; the unhardened portions of the photo-sensitive material are washed away; and the copper sheet is etched through in place exposed by the washing.

If control electrode 25 is biased at a direct potential slightly below that of retarding electrode 24, small fluctuations in its potential can be made to current-modulate the current from each of the films 26 of electrode 24. This control is possible because the secondary electrons have very low velocities. On the other hand, such fluctuations will not significantly influence electron jets which pass through the open apertures of retarding electrode 24. In other words, they will not affect any electrons which reach it without being "retarded" by a secondary emit-

ter film. Thus, the present invention provides a means for the selective control of electron jets according to their positions.

For electrode 25 to current-modulate slow electron jets, the electrode in front of it should be at a higher direct potential than the retarding electrode which emitted those jets. In this way, each jet of secondary electrons from electrode 24 will "see" a positive field through an aperture of electrode 25. And, of course, the geometry and intensity of this field will be a function of the potential of this control electrode.

The electrode next ahead of control electrode 25 is an intermediate retarding electrode 27. From what has preceded and what is to follow, it will be apparent that this next electrode 27 has two functions: a principal one as a "retarder" of certain fast jets emitted from normalizing electrode 21, and a subordinate one as an accelerator for certain slow secondary jets emitted from retarding electrode 24. More specifically, it is a "retarder" for jets which are directed toward the G coatings, and an accelerator for jets which are directed toward the R coatings. If desired for any reason, separate electrodes could be used to perform these respective functions.

An intermediate control electrode 28 is positioned in front of retarding electrode 27. These two electrodes co-operate in what may be considered a second stage for the selective control of electron jets according to their positions. Similarly, two more electrodes co-operate in a third stage for selective control. These electrodes, a front retarding electrode 29 and a front control electrode 30, are positioned in front of the intermediate control electrode 28 in the order named.

Since the back, intermediate and front retarding electrodes are at slightly ascending potentials, the electron jets which they respectively "retard" will have progressively slightly higher energies. This does not present any significant difficulty. It merely necessitates the use of slightly different values of bias between each retarding electrode and its associated control electrode.

Ahead of front control electrode 30 is a front accelerating electrode 31. In the operation of tube 10, it provides the positive field required for the proper operation of this control electrode.

Tests have indicated the following to be suitable operating potentials for electrodes 21, 24, 25, 27, 28, 29, 30 and 31 and the target 17 respectively (as related to that of the electron-gun cathode as a reference): +3000 volts; +6000 volts; about +5990 volts; +6200 volts; about +6190 volts; +6400 volts; about +6390 volts; +6600 volts; and +15,000 to +25,000 volts.

When target 17 is spaced in front of the front accelerating electrode by as much as .125 to .200 inch, each jet of electrons impinges accurately on a desired predetermined coating R, G, or B if an accelerating voltage of as much as 10,000 volts is established across this space. Moreover, any increase in this voltage permits an increase in this spacing and vice versa. Therefore, this arrangement affords in tube 10 a means for attaining high-level target excitation by post-acceleration. As a result, the beam electrons do not need to attain more than a relatively low range of velocities while still moving through neck 12. Therefore, tube 10 operates satisfactorily with the provision of less deflection power for its yoke 32 than is possible with a tube which does not use post-acceleration but otherwise is similar to tube 10.

The electrodes of control assembly 16 may be

assembled in exact registry by the use of a number of sapphire rods 34 as shown in Fig. 2. This is possible because the same pattern of apertures is used for all of the electrodes. However, since target 16 is not apertured, its supporting structure, glass plate 18, must have holes specially drilled for receiving the sapphire rods. Accordingly, a particular order of assembly is suggested for obtaining excellent registry. The holes are drilled somewhat oversize, and rods 34 are set in soft cement in these holes. The rods are positioned accurately (while the cement is still soft) by using an apertured plate as a template. They are kept in these positions until the cement 35 hardens. A first settling mask is placed over the back surface of the plate. It has one-third as many apertures as plate 22 and the pattern of its apertures corresponds to the pattern of positions for one of the sets of coatings. This mask is guided to an exact desired position on plate 18 by the sapphire rods 34. The sets of coatings in question R, G, or B, is then settled (or sprayed, or dusted, or squeegeed) onto plate 16 through the mask. The last two steps are repeated with second and third masks for forming the other two respective sets of coatings.

Thereafter, a number of ring-shaped mica washers 36 are placed over the respective rods adjacent plate 18 to fix the distance between accelerating electrode 31 and the back surface of the target 17. Thereafter, electrodes 30, 29, 28, 27, 25, 24 and 21 are slipped over the sapphire rods in the order named with a ring-shaped mica washer 37 fixing the spacing between each pair of adjacent electrodes. The normalizing electrode 21 is cemented to the back ends of the rods 34 (as shown at 38) while the elements of assembly 16 are urged compactly together.

Where large-diameter electrodes are used, small glass balls 39 may be cemented between adjacent electrodes to fix a predetermined minimum spacing between them at different points on their apertured central portions. Each ball may be captive between a pair of apertures and further held in place by cement.

In Fig. 3 there is shown a modification of the tube of Fig. 1. In this embodiment no normalizing electrode 21 is used. Instead, in operating this tube 10' the conductive coating 20' and the back selective retarding electrode 24' are polarized at different direct potentials to establish a large-diameter electrostatic normalizing lens in the region immediately behind assembly 16'.

In addition, this embodiment has no electrode corresponding to the final accelerating electrode 31 of Figs. 1 and 2, target 17 being relied on to perform its accelerating function. This is not to be preferred, because the very high positive potential at which the target 17 is maintained during operation will require the use of larger amplitude video voltages for proper operation of control grid 30'.

It will be apparent from the foregoing that the coatings R, B, G for target 17 may be laid down in strips, as shown in Fig. 6, or in dot-like patches as shown in Fig. 7 when the apertures of the control assembly electrodes are arranged in a pattern of parallel and perpendicular rows as shown in Fig. 7. However, the sub-elementary coatings and the apertures may be arranged in any of a great variety of possible patterns as long as they correspond to each other. For example, if desired, the apertures may be positioned in parallel rows which intersect each other at 60 (and 120) degrees as shown in Fig. 5, and the coatings R, G

and B may be staggered as shown in Fig. 8 so that each picture element is a small triangle having a patch of a different kind of coating material at each of its apexes. Of course, where the coatings R, B, G are positioned in this way the locations of the films 26 on the various retarding electrodes must be in appropriate correspondence.

Where a target 17' of the type shown in Fig. 9 is used, i. e., a target having a single uniform fluorescent coating, this coating is formed of a mixture of material capable of emitting light components extending well over the visible spectrum. Moreover, the sub-elementary parts R', B', G' of the optical filter which is used with such a single coating are arranged in patterns corresponding in any embodiment to the combination of patterns used for the positions of the films 26 on the several retarding electrodes.

It is not necessary for the secondary emitter films used herein to be coated with activated compounds as is done with an electron multiplier "dynode" which emits secondary electrons from its bombarded side. The one thing that is essential is that the films be thin enough to afford a satisfactory secondary emission ratio (at least a value not much under 1) where bombarded with primary electrons having velocities of the order of two or three thousand volts. Another is that they should not be so thin and/or have so many "pinholes" that a substantial percentage of such primary electrons will penetrate entirely through and not be "retarded."

It may be noted that not all of the secondary electrons are emitted along normal paths (to be specific, their directions of emission have a dispersion according to a cosine law). However, the paths actually taken by these slow-moving electrons soon after they leave the secondary emitter films are almost entirely forward since the accelerating fields which they encounter are many times greater than their own initial velocities (about 200 to 5).

If desired, tube 10 of Fig. 1 may be operated in the manner described above with respect to tube 10' of Fig. 3. That is, it may be operated so as to establish an electrostatic lens immediately back of control assembly 16. To do this, it is necessary to sever the direct connection 40 shown in Fig. 1. In such operation, two separate means are acting simultaneously to "normalize" the scanning beam. Therefore, optimum results are obtained in this respect.

In Fig. 5 a small part of the electrode nearest to the front of a control assembly, e. g., a front accelerating electrode in a Fig. 2 embodiment or a front control electrode in a Fig. 4 embodiment is represented as seen through a magnifying glass. This is done to emphasize the fact that the apertures are so small and so close together that they are not easily seen with the naked eye. Actually, the enlargement represented in Fig. 5 is grossly exaggerated and is more in accordance with what would be achieved with a microscope. Fig. 5 also shows clearly a number of tabs 41 each of which serves as a conductive lead for a respective electrode of the control assembly. One of these tabs also appears in Fig. 2; one terminal pin 42 is sealed through the cone 13 in a position opposite each of the tabs 41 and its inside end is connected thereto. Thus means are provided for connecting each electrode to an external circuit element.

In one way of operating tube 10 the electron beam from gun 15 is scanned over the back of the control assembly 16 without being either

current-modulated or keyed. The determination of picture-element values for the respective interlaced monochromatic images is effected at the control electrodes 25, 28, 30. For example, these electrodes may be respectively connected to individual video signal sources 43, 44, 45 each of which provides a train of positive going impulses which are amplitude-modulated to represent the picture-element values of a different monochromatic image. If each of these electrodes is biased a little below cut-off, these impulses effect both sequential color switching and selective video modulation.

The color switching may be at either an element sequential, a line sequential or a pulse sequential rate. Moreover, simultaneous operation is also possible because of the subdivision of the beam into several jets, each of which can cause light emissions of a different color. For such operation, the separate video signals are not pulsed and the control electrodes are biased for class A density-modulation.

Another manner of operation is illustrated in Fig. 3. Appropriately-phased color-switching signals, such as three-phase sine waves, are applied to the control electrodes 25', 28' and 30' from individual sources 46, 47 and 48. At the same time a multiplex color video signal (i. e., a composite polychromatic video signal) from a common source 49 is applied to gun 15 while it is biased for class A operation.

I claim:

1. A color-television tube comprising an image surface consisting, effectively, of a multiplicity of duplicate groups of sub-elemental areas of different color-response characteristics, a source of beam-electrons directed toward said surface, a control assembly including at least two apertured plates mounted in successive array adjacent to said surface with the apertures of said plates in register with individual ones of said sub-elemental color-areas, means including one of said apertured plates for dividing said beam into a plurality of sets of electron-jets, each set individual to surface areas of a particular color-response characteristic, and means including another of said apertured plates for controlling a predetermined one of said sets of jets.

2. The invention as set forth in claim 1 and wherein said last-mentioned means comprises a retarding electrode mounted adjacent to said second-mentioned apertured plate, on the side nearest said source, for effectively retarding the jets of said selected set, and wherein means are provided for applying to said second-mentioned apertured plate a current modulating potential for said effectively retarded jets.

3. A color-television tube comprising an evacuated envelope containing an image surface consisting, effectively, of a multiplicity of duplicate groups of sub-elemental areas of different color-response characteristics, an electron gun for projecting a beam of electrons toward said surface, a control assembly mounted adjacent to said surface between it and said gun, said assembly comprising means including an apertured plate for effectively subdividing a beam from said gun into a plurality of sets of electron jets each individual to surface areas of a particular color-response characteristic, and a plurality of means for current-modulating said sets of electron jets independently of each other.

4. A cathode ray device as in claim 3 which further comprises means for normalizing said jets with respect to a planar reference of said

assembly for different angles of approach of said beam toward said target from said gun.

5. A color television tube comprising an image surface consisting, effectively, of a multiplicity of duplicate groups of sub-elemental areas of different color-response characteristics, a source of electrons directed toward said surface, a control assembly including at least two apertured plates mounted in successive array adjacent to said surface, means including one of said apertured plates for effectively subdividing the supply of electrons derived from said source into a plurality of sets of electron jets, each individual to surface areas of a particular color-response characteristic, a plurality of means each including another apertured plate for effectively retarding selected of said sets of jets, and means including a control electrode between each retarding electrode and said surface for current-modulating each of said selected sets of retarded jets.

6. A discharge device as in claim 5 which further comprises a target electrode having a conductive surface as a support for said image surface and means connectable to an external source of potential for polarizing said conductive surface at a different direct potential than any of the electrodes of any of said means for controlling selected sets of jets.

7. A color-television tube comprising an evacuated envelope containing an image surface, consisting effectively of a multiplicity of groups of sub-elemental areas of different color-response characteristics, an electron gun for projecting a beam of electrons toward said surface, a control assembly mounted adjacent said surface between it and said gun, said assembly comprising means including an apertured plate for effectively subdividing a beam from said gun into a plurality of sets of electron jets, each individual to sub-elemental surface areas of a particular color-response characteristic, a plurality of means for individually controlling selected sets of jets, each of said last-mentioned means including an electrode for effectively retarding one set of selected jets predetermined according to the color-response characteristic of the sub-elemental areas allotted to said set, a control electrode between the retarding electrode and said surface for current-modulating only jets which have been effectively retarded at said retarding electrode, each retarding electrode comprising a plate having a plurality of apertures each of which is aligned with a different aperture of said first mentioned plate and secondary emitter films covering particular ones of its apertures toward each of which selected jets of a different set thereof move from said first-mentioned plate.

8. A color-television picture tube comprising an evacuated envelope containing an image surface, consisting effectively of a multiplicity of duplicate groups of sub-elemental areas of different color-response characteristics, an electron gun for projecting a beam of electrons toward said surface, a control assembly, at least two parallel apertured plates mounted adjacent to said surface between it and said gun, said assembly comprising means including one apertured plate for effectively subdividing a beam from said gun into a plurality of sets of electron jets, each individual to surface areas of a particular color-response characteristic, and a plurality of means each including another apertured plate for individually controlling selected sets of jets predetermined according to the color-response characteristic of the sub-elemental areas allotted to

said set, means in the path of said beam for normalizing said jets with respect to said first-mentioned plate for a variety of angles of approach of said beam toward said plate.

9. A color television picture tube as in claim 8 in which said means for normalizing comprises a secondary emitter film in the path of electrons tending to pass through each of said apertures and responsive thereto to emit a jet of secondary electrons therethrough from the side of the film facing said image surface.

10. A color television picture tube as in claim 8 in which said means for normalizing comprises at least two juxtaposed electrodes of substantially circular symmetry for producing a large-diameter electrostatic lens in a region adjacent to said assembly and between it and said electron gun when they are polarized at different direct potentials.

20 11. A color television picture tube comprising an evacuated envelope, said envelope containing a target electrode having an image surface, an electron gun for projecting a beam of electrons toward said surface, a plurality of sub-elementary monochromatic fluorescent coatings, carried on said surface to form a polychromatic screen, said plurality of coatings comprising at least two discrete sets thereof in which all of the coatings of each set fluoresce in the same color and the coatings of the different sets fluoresce in different colors, said coatings being positioned on said surface in groups, each group including one coating of each set arranged so as to constitute a polychromatic screen element, a control assembly mounted adjacent said surface between it and said gun, said assembly comprising means including an apertured plate for effectively subdividing said beam into at least as many jets as the number of said coatings in one group, means including said apertured plate for directing each jet toward a particular coating, at least as many jet-current control means as the number of said sets of coatings, each of said last-mentioned means including an electrode for effectively retarding a set of jets which are directed toward coatings of the same set thereof, and a control electrode between the retarding electrode and said target electrode for controlling only jets which are effectively retarded by said retarding electrode.

50 12. A picture tube as in claim 11 in which said groups of coatings are positioned in a pattern of lines corresponding to a raster to be scanned by said beam in the operation of the tube.

55 13. A color television picture tube comprising an evacuated envelope containing a target electrode having an image surface, an electron gun for projecting a beam of electrons toward said surface, a fluorescent screen carried on said surface, a light filter comprising a plurality of sub-elementary parts for filtering light emitted from sub-elementary portions of said coating said plurality of parts comprising at least two discrete sets thereof in which all of the parts in each set selectively transmit light of the same color and the parts of the different sets selectively transmit light of different colors, said parts being positioned with respect to said image surface in groups, each group including one part of each set arranged so as to constitute an interlaced polychromatic screen element, a control assembly mounted adjacent said surface between it and said gun, said assembly comprising means including an apertured plate for effectively subdividing said beam into at least as many jets

as the number of said filter parts in one group, means including said apertured plate for directing each jet toward an area of said fluorescent coating registered with a particular part of said filter, at least as many individual jet-density control means as the number of said sets of filter parts, each of said last-mentioned means including an electrode for effectively retarding a set of jets which are directed toward coating areas registering with filter parts of the same set, and a control electrode between the retarding electrode and said target electrode for controlling only jets which are effectively retarded by said retarding electrode.

14. A cathode-ray discharge device comprising a source of electrons, means for deriving a beam of electrons from said source, means for imparting a scanning movement to said beam, a control assembly mounted in the path of scan of said beam, said control assembly comprising means including an apertured plate for effectively dividing said beam into a plurality of sets of electron jets whose axes are substantially normal to said plate, and a plurality of jet-intensity control means, each including another apertured plate parallel to said first mentioned plate, for selectively controlling said sets of jets in accordance with the positions of the intersection of their axes with said first mentioned plate.

15. An electron discharge device comprising an electron-sensitive screen having a foundation surface containing a multiplicity of sub-elementary phosphor areas, a stack of mutually insulated foraminous electrodes mounted with their holes in alignment with each other and with individual ones of said phosphor areas to provide a multiplicity of discrete passageways through which electrons may pass to said individual ones of said phosphor areas, a secondary-electron emissive means in each of said passageways, and a source of electrons common to said passageways for energizing said last means whereby secondary electrons which are emitted therefrom selectively energize said sub-elementary phosphor areas of said screen.

16. An electron discharge device comprising an evacuated envelope containing a target surface

having a multiplicity of sub-elementary electron-sensitive image-areas thereon, means for directing electrons toward said target surface, an array of foraminous electrodes mounted in mutually insulated relation in the space between said electron source and said target surface, the holes in said foraminous electrodes being disposed in alignment with each other and with individual ones of said image-areas to provide a multiplicity of discrete passageways through which electrons may pass as separate jets to said individual ones of said image-areas, and means for impressing different current-modulating potentials upon respective ones of said mutually insulated foraminous electrodes for selectively controlling different sets of said jets.

17. A television tube comprising a sealed envelope containing an electron-sensitive surface including a number of sub-elementary image areas, emissive means spaced from said surface for providing a flow of electrons toward said image areas, a structure mounted between said emissive means and said surface and having a number of electron passages each providing a respective path from the emissive means to a different sub-elementary area, an apertured plate lying athwart said passages and including retarding means aligned with a predetermined number less than all of said passages for effectively retarding electrons moving therethrough, and a foraminous control electrode adjacent the side of said apertured plate toward said surface.
